ATTY.

UNITED STATES PATENT OFFICE.

WILLIAM MORTON BUCKLEY, OF WINNIPEG, MANITOBA, CANADA.

GARMENT.

1,131,674.

Specification of Letters Patent.

Patented Mar. 16, 1915.

Application filed June 18, 1912. Serial No. 704,277.

To all whom it may concern:

Be it known that I, WILLIAM M. BUCKLEY, a subject of the King of Great Britain, and resident of the city of Winnipeg, in the 5 Province of Manitoba, in the Dominion of Canada, have invented certain new and useful Improvements in Garments, of which the following is the specification.

My invention relates to improvements in 10 garments and more particularly to sweaters, sweater coats or the like and the object of the invention is to devise a sweater or the like in which the collar can be turned down to form a collar of the sailor type or which 15 can be buttoned up close to the throat when desired.

A further object is to devise a collar which can be turned into a hood when required.

Figure 1 shows a front view of a garment 20 constructed according to my invention showing the collar turned down to form a sailor collar. Fig. 2 is a back view thereof showing the buttons and button holes on the back edge of the collar. Fig. 3 is a front view 25 of the collar buttoned up close to the throat. Fig. 4 is a back view thereof. Fig. 5 is a front view showing the collar turned up to form a hood, and Fig. 6 is a side view thereof.

Like characters of reference indicate corresponding parts in the different views.

1 is the garment having the collar 2.

3 are a plurality of button holes adjacent to the back edge of the collar. 4 are a plurality of buttons on the other side of the opposite side of the collar adjacent to the back edge. 5 are a plurality of button holes near the front edge of the collar adjacent to the neck band and 6 are a plurality of buttons on the opposite side thereof.

It will be seen that a collar constructed according to my invention can take up three separate and distinct positions; firstly, it can be turned down into the ordinary sailor collar, and secondly, it can be closed up at 45 the throat to protect the same by buttoning the buttons 6 into the button holes 5, and thirdly, it can be turned into a hood when desired by turning up the collar and buttoning the buttons 4 into the button holes 3 50 and buttoning the buttons 6 into the button holes 5.

Although the article is shown with buttons and button holes it is to be understood that dome fasteners or other suitable fasteners may be used in place thereof.

What I claim as my invention is:

In a garment, an adjustable sailor collar having a plurality of button holes extending half across the same and adjacent to the 60 back edge thereof, a plurality of buttons on the under side of the opposite half of the collar and adjacent to the back edge thereof, a plurality of button holes in one of the front edges of the collar adjacent to the neck 65 band, a plurality of buttons on the other front edge of the collar adjacent to the neck band and on the under side thereof, the said collar being adapted to be closed up to the throat when the last said buttons and button-holes are in engagement and being designed to form a hood when the first said button and button-holes are also engaged, substantially as described.

In witness whereof I have hereunto set my 75 hand in the presence of two witnesses.

WILLIAM MORTON BUCKLEY.
